RAIL ELEVATING DEVICE

Walter T. Hake and Howard E. Laubach, Cincinnati, Ohio, assignors to American Steel Foundries, Chicago, Ill., a corporation of New Jersey

Application November 1, 1954, Serial No. 465,910

6 Claims. (Cl. 77—4)

The invention relates to a novel device incorporated in a rail elevating mechanism on a vertical boring mill and particularly to an arrangement to facilitate the leveling of the rail at any given position on the mill.

As will be well understood by those skilled in the art, a vertical boring mill generally comprises a pair of vertically extending columns upon which is mounted a generally horizontal rail, said rail being movable up and down on ways provided on said columns, whereby a rail head carried tool may be moved toward and away from a generally horizontal rotatable work table. The rail head on the rail is additionally power movable in a generally horizontal direction across the rail, said rail being provided with horizontal ways to facilitate said movement. In this manner, the carried tool may be brought horizontally across a table mounted work piece to provide for cutting the desired contour on said work piece. Inasmuch as the rail head is movable horizontally on the rail, it becomes particularly important to maintain the rail itself and especially the ways formed on the rail which guide the movement of the rail head, in an exact level or horizontal relation relative to the surface of the rotating work table.

As earlier noted, the rail itself is vertically movable on the columns, said movement being afforded by a generally vertically arranged power driven screw which is received by the rail and threadably engaged therewith, whereby upon rotation of the screw, the rail is urged upwardly or downwardly depending on the direction of the screw rotation. In many mills of the type here under consideration, the rail is extremely large and bulky; hence, it requires a plurality of vertical screws, usually one in each column, threadably engaging the rail at spaced points to accomplish the desired vertical movement. With the extreme requirement for holding the rail level at a plurality of positions on the column, it becomes a difficult, if not an impossible, task to so machine the vertical screws and the receiving threads on the rail, so that as the screws are rotated and the rail moved vertically, the rail ways are maintained in said level position. Accordingly, it is desirable to provide means whereby the rail may be leveled at any given selected point on the supporting columns by the expedient of raising or lowering one side of the rail as desired.

Heretofore in the art, it was necessary, when it became desirable to level the rail, for the operator to climb to the top of the machine, remove the covers on the machine crown, and by a complicated adjusting nut and locking nut arrangement to vertically raise or lower one of the adjusting screws whereby the associated end of the rail would be moved in the desired direction. This has been a complicated and time wasting procedure in view of the fact that many settings must be tested before the rail is accurately leveled, requiring, in the usual instance, either the services of two men, namely, one to adjust and one to indicate the level of the rail, or in the alternative a single operator would be required to scramble up

2
and down the machine a number of times to achieve the desired setting.

The herein concerned invention contemplates a new and simple arrangement whereby the rail of the vertical boring mill may be easily leveled at any position on the mill by a single machine operator. It is, therefore, a primary object of the invention to provide a novel rail elevating arrangement with a unique leveling mechanism associated therewith.

It is a specific object of the invention to provide an arrangement of the type described, wherein the operating parts are located at the back of the rail and are easily accessible to the machine operator while on ground level.

It is an additional specific object of the invention to provide a novel bracket-adjusting bushing arrangement to receive and engage the vertical screws on a vertical boring mill, said arrangement facilitating the leveling of the horizontal rail.

These and other objects of the invention will become apparent in the course of the following description and from an examination of the concerned drawings, wherein:

Figure 1 is a fragmentary end elevational view illustrating the horizontal rail of the boring mill and its operative connection to the vertical screw;

Figure 1a is a front perspective view of a vertical boring mill;

Figure 1b is a front view of the crown portion of a vertical boring mill partially broken away to show the power means carried thereby;

Figure 2 is a fragmentary top view taken along line 2—2 of Figure 1;

Figure 3 is a fragmentary view of the screw and rail mounted receiving member but illustrating another embodiment of the invention;

Figure 4 is a fragmentary top view taken along line 4—4 of Figure 3;

Figure 5 is a fragmentary top view illustrating another embodiment of the invention; and

Figure 6 is a fragmentary elevational view of the structure shown in Figure 5.

The herein disclosed invention has particular utility, as above noted, when associated with a vertical boring mill, and due to the fact that those skilled in the art are generally familiar with the function, operation, and construction of a vertical mill, it has been thought expedient in the drawings to disclose in detail only that portion of the vertical mill illustrating in detail the novel leveling mechanism associated with the rail elevating device. It also should be noted that in certain of the figures, features of construction may be omitted where it is believed said features are more accurately and adequately disclosed in other figures.

Describing the invention in detail and directing attention first to Figures 1a and 1b, it will be seen that the mill comprises a base portion 3 adapted to carry a rotatable work supporting table 5. The mill further comprises spaced vertical columns 4, said columns having a front face 6, said face 6 being machined to provide a way on which is mounted a rail 8. The rail 8 is movably mounted on the face 6 whereby it is guided for vertical movement, by means of screws 16, up and down depending on the particular operation of the machine. The columns 4 have a crown 10 mounted thereon, said crown 10 having positioned therein a power mechanism 11, Figure 1b, which serves to drive a horizontally arranged shaft 12, said shaft 12 having a worm gear formed on the periphery thereof, said gear engaging a complementally formed gear 14 mounted on the upper end of a vertical screw 16 (Figures 1 and 1b). The gear 14 is keyed or nonrotatably locked to the upper end of the screw 16 and a retaining nut 18 locks the assembly firmly in place,

Immediately below the gear 14, a plurality of bearings 20 and 21 are provided, said bearings being mounted in the crown 10, whereby they offer rotatable support for vertical screw 16.

It will be noted that the bearing 20 primarily serves to accommodate rotative movement of the screw 16, whereas the bearing 21 is arranged to act as a thrust bearing and accommodate and resist vertical forces carried by the screw 16. The screw 16 extends generally downwardly whereat it is received within an aperture 24 formed in a rail mounted bracket, indicated generally at 26. The aperture 24 is preferably cylindrical in cross section and is arranged to receive the body 28 of an adjustment bushing, indicated generally at 30. The body 28 of the adjustment bushing 30 presents a peripherally cylindrical surface which is complementally and closely fitted within the aperture 24 of the bracket 26. At the lower end thereof, the bushing 30 is provided with a radially extending flange 32, said flange 32 abutting the lower side of the bracket 26. The body 28 of the bushing 30 extending upwardly through and above the aperture 24, whereat it presents on its external peripheral surface, screw threads 34, said screw threads 34 threadably engaging a positioning nut 36, said nut 36 being arranged to abut the other side of the bracket 26, whereby the nut and flange are urged to tightly clasp the bracket.

As earlier noted, the screw 16 is provided with a continuous series of threads on its outer periphery preferably an Acme type thread. The screw is received within an aperture or vertical opening 38 centrally formed within the adjustment bushing 30. The opening 38 is provided with threads 40 which complementally engage the threads provided by the screw 16. Directing attention to Figure 1, it will be seen that the bracket 26 is provided with a vertical slot 42 in one side thereof, said slot 42 communicating with the aperture 24 formed in the bracket and dividing the bracket into two sections 44 and 46. The sections 44 and 46 have aligned apertures 48 and 50 formed therein, said aligned apertures receiving a bolt 52. The bolt 52 abutably engages the section 46 by means of a wing 54 which receives the head of the bolt. Additionally, the bolt 52 is threadably connected to the aperture 48 as at 56. With this arrangement the bolt 52 may be tightened, whereby the section 46 is sprung inwardly toward the section 44 which results in the frictional engagement of the inner periphery of the aperture 24 with the outer periphery of the body 28 of the adjusting bushing 30. It will also be noted that the flange 32, as well as the nut 36, are provided with a plurality of angularly spaced holes 58 and 60, respectively, said holes serving to receive a spanner wrench or other convenient tool for rotation of the particular member, as will herein-after be more fully described.

When it is desired to adjust the relative or static position of the rail and the screw 16, the machine operator merely loosens the bolt 52 which releases the friction hold of the section 46 on the bushing 30. With an appropriate tool, he then rotates the nut 36 to a released position. This leaves the bushing 30 free to be rotated upon the screw 16. If it is desired to raise the associated end of the rail, the bushing 30 is rotated in a counterclockwise direction, as seen in Figure 2, which carries the bracket 26 and attached rail end vertically relative to the screw 16. When the rail is indicated level, the operator then tightens the nut 36 and may lock said nut in position by means of a set screw at 62. The operator then tightens the bolt 52 to positively insure that the adjusting bushing 30 will not rotate during screw action and destroy the rail level.

Directing attention to Figures 3 and 4, which illustrate another and perhaps preferred embodiment of the invention, it will be seen that the screw 16 and the receiving bracket 26 are substantially similar to that of the embodiment illustrated in Figures 1 and 2. The adjusting bushing 30 is again disposed in the aperture

24 of the bracket, and the bushing is provided with a flange 32 at its lower end and a locking nut or positioning nut 36 at its upper end. The detail of the locking arrangement whereby the adjusting bushing 30 is non-rotatably positioned within the bracket 26 differs in this embodiment. It will be seen that the bracket 26 is provided with a generally horizontal bore 68, said bore having an axis angularly arranged to the axis of the bushing receiving aperture 24. A locking bushing, indicated generally at 70, is disposed within the bore 68, said bushing 70 comprising separated sections 72 and 74. The sections 72 and 74 are provided with centrally located aligned apertures in which is disposed a machine bolt 76. The bolt 76 is provided with a head which abuts the end of the section 74 and is threadably engaged with the inner periphery of the section 72. The locking bushing 70 and particularly the sections 72 and 74 are provided with arcuate surfaces 78 and 80, said surfaces being exposed to the internal periphery of the aperture 24, whereby said arcuate surfaces may be engageable with the external periphery of the adjusting bushing 30.

The rail elevating or leveling operation of this embodiment is identical with that heretofore described. However, when it is desired to lock the adjusting bushing in a determined position, the operator merely rotates the screw 76 which urges the sections 72 and 74 of the locking bushing 70 toward one another and into tight frictional engagement with the periphery of the adjusting bushing 30 at surfaces 78 and 80.

30 Directing attention to Figures 5 and 6, which illustrate another embodiment of the invention, it will be seen that the bracket 26 now comprises a rail mounted section 84 and a demountable cap section 86. An aperture 88 is defined within the bracket 26 by the sections 84 and 86, 35 said aperture 88 again receiving an adjusting nut 90, the adjusting nut 90 is provided with a flange 92 which abuts the lower end of the bracket 26 much the same as in previous embodiments. Additionally, the flange 92 is provided with gear teeth around the outer periphery thereof, said teeth being operatively engaged with the gear teeth provided by a worm gear indicated at 94. The worm gear 94 is mounted on a shaft 96, said shaft 96 locking itself in the rail mounted bracket 98, and said shaft being rotatable in said bracket to provide for the rotation of the mounted worm gear 94. A hex head 100 or similar device is provided on one end of the shaft 96 to offer convenient means whereby a tool may clamp the shaft and the shaft may be rotated. Upon rotation of the shaft 100, the worm gear 94 is urged to rotate which in turn rotates the engaged adjusting bushing 90 which provides for relative adjustment by the screw 16 and the associated end of the rail. It will be appreciated that the mechanical adjustment features of this embodiment could readily be accommodated to the embodiment heretofore described.

55 It will be noted that the cap section 86 of the bracket 26 frictionally grips the external periphery 102 of the adjustment bushing 90 when the bolts 104 are fixedly locked in place. Therefore, it will be understood that in this embodiment, when it is desired to make the adjustment to level the rail, the bolts 104 must be loosened to provide for the rotation of the adjustment bushing 90.

60 Thus it will be seen that I have provided a novel mechanical arrangement which readily accommodates the leveling of a rail in a vertical boring mill, whereby a single operator may easily and quickly accomplish the desired rail leveling which is necessary to proper and accurate machining in view of the fact that the arrangement is novel and conveniently located on the boring mill rail in a location of ready accessibility as differentiated from the arrangements heretofore employed in the art.

70 We claim:

75 1. In a rail elevating device for use on a vertical boring mill having a table rotatable about a vertical

axis, a horizontal rail movable vertically on column ways provided on the rail, a pair of rail elevating screws, power means to drive said screws in unison, at least one bracket secured to the rail for movement therewith, said bracket having an opening adapted to receive therethrough the related screw, a bushing rotatably received within the opening and threadably engaging the screw, said bushing having a flange at one end thereof abutting the adjacent side of the bracket, a positioning nut threadably mounted on the other end of the bushing and engageable with the other side of the bracket whereby upon loosening of said nut, said bushing may be rotated to adjust the position of said rail on said screw and whereby said flange and nut may be drawn into tight engagement with said bracket, and means to lock said device in adjusted position.

2. A rail leveling device according to claim 1, wherein said locking means comprises a slot in one side of said bracket communicating with said opening and dividing said bracket into sections, and means to spring said sections toward each other whereby the internal periphery of the bracket is urged to frictionally engage the outer periphery of the bushing.

3. In a rail leveling device for use on a vertical boring mill having a table rotatable about a vertical axis, the combination of a pair of column ways on the mill, a horizontally disposed rail movable vertically on said ways, a pair of rail elevating screws disposed at opposite ends of said rail, said screws being rotatable in unison, and independent leveling means associated with at least one screw for raising or lowering the associated end of the rail, for leveling purposes, without rotating the screw, said leveling means comprising a bracket secured to the rail adjacent the screw, said bracket having an opening therethrough receiving the respective screw, a bushing rotatably disposed within said opening and threadably engaging the screw, said bushing being opera-

5

tively engageable with said bracket whereby, upon rotation of said bushing, said bracket is moved axially of said screw, and means to lock the bushing in a fixed position relative to the bracket.

4. A rail leveling device according to claim 3, wherein said locking means comprises a bore in the bracket having its axis angularly disposed relative to the axis of said opening, said bore communicating with said opening, and a locking bushing in said bore to frictionally engage the outer periphery of said first mentioned bushing.

5. A rail leveling device according to claim 3, and including a flange at one end of said bushing abutting the adjacent side of said bracket, gear teeth peripherally formed on said flange, a worm gear rotatably mounted on the rail and adjacent to and in engagement with said gear teeth, and means to rotate said worm gear whereby said bushing may be rotated.

6. A rail leveling device according to claim 5, wherein said locking means comprises a split collar having a rail mounted section and a demountable cap section, and a plurality of bolts operative to tightly mount said cap section on said rail mounted section whereby said bushing is frictionally engaged by the inner periphery of said bracket.
